UNITED STATES PATENT OFFICE.

JOHN W. BERWICK, OF NEW YORK, N. Y.

DESIGN FOR A BOX.

44,431.

Specification for Design.

Patented Aug. 5, 1913.

Application filed March 29, 1913. Serial No. 757,715. Term of patent 7 years.

To all whom it may concern:

Be it known that I, JOHN W. BERWICK, a subject of the King of Great Britain, citizen of the Dominion of Canada, residing at New York, county of Kings, State of New York, United States of America, have invented a new, original, and ornamental Design for a Box, of which the following is a specification, reference being had to the accompanying drawing, forming a part hereof.

The drawing is a perspective showing a box formed in accordance with my design.

I claim—

The ornamental design for a box, as shown.

JOHN W. BERWICK.

Witnesses:

F. D. AMMEN,
BEATRICE MIRVIS.
